UNITED STATES PATENT OFFICE.

HAROLD EDENBOROUGH, OF BATTERSEA PARK, LONDON, ENGLAND.

HOLDER FOR EMERY-CLOTH AND THE LIKE.

1,181,123.

Specification of Letters Patent.

Patented May 2, 1916.

Application filed June 8, 1915. Serial No. 32,810.

To all whom it may concern:

Be it known that I, HAROLD EDENBOROUGH, engineer, a subject of the King of Great Britain, residing at 89 Prince of Wales Mansions, Battersea Park, London, England, have invented certain new and useful Improvements in Holders for Emery-Cloth and the like, of which the following is a specification.

10 This invention relates to holders or means for mounting and holding emery cloth or the like on files or other supports; and has for its object to provide holders or means consisting of readily attachable or detachable devices for the aforesaid purposes of simple and economical character and specially designed and adapted for mounting and holding emery cloth on any ordinary file (without requiring any alteration or 20 modification of the latter) or the said devices may be employed for mounting and holding emery cloth or the like on any other body or backing (i. e. other than a file) adapted to serve as a support of said emery cloth or the 25 like while in use which support (or file) may be of any desired or suitable width and length or shape.

The present invention comprises (1) a special gripping device or means (hereinafter referred to as the "grip") adapted (a) to be readily attached to and detached from the tang or shaft or handle end of any ordinary file or the like or any other suitable body or backing adapted to serve as a 35 support (all of which I will hereinafter refer to as the "file") for the emery cloth or the like and (b) to have one end of the said emery cloth or the like attached thereto and detached therefrom and (2) an attachment 40 plate or gripping device (which I will hereinafter refer to as the "emery cloth attaching plate") adapted (a) to have attached thereto the other end of the strip of emery cloth or the like and after the latter has 45 been stretched taut over the outer end of the file adapted (b) to be fitted onto and held by a part or parts of the first-named "grip" or gripping device—so as thus to hold the emery cloth or the like stretched 50 taut on both sides of the file or the support. In addition a clip or slide is provided adapted to fit or slip over the emery cloth or the like folded over the end of the file; and this clip or slide may be used in conjunction

either with the first-named special gripping device or in conjunction with the two aforesaid devices as hereinafter explained.

For the sake of example I will now describe with reference to the accompanying drawings my invention as carried into practice for attaching a piece (strip or sheet) of emery cloth, sand or glass paper or the like for example a leather strip provided with abrading material for burnishing (all of which I will hereinafter refer to as "emery cloth") over one or both faces of an ordinary file.

Referring to the accompanying drawings:—Figure 1 is a perspective view of the "grip" adapted to be attached to and detached from the ordinary tang of a file. Fig. 2 is a perspective view of the aforesaid clip or slide adapted to fit or slide over the outer end of the file and emery cloth thereon. Fig. 3 is a perspective view of the file having a strip of emery cloth secured over one face thereof by the aforesaid "grip" Fig. 1 and slide Fig. 2. Fig. 4 is a perspective view of a similar "grip" to Fig. 1—slightly modified. Fig. 5 is a perspective view of the emery cloth attaching plate. Fig. 6 is a perspective view of a file showing method of attaching a strip of emery cloth over both faces of said file by means of the aforesaid devices illustrated in Figs. 4 and 5.

Referring more particularly to Figs. 1-3, the "grip" (Fig. 1) comprises a flat plate or portion A adapted to extend from the tang end of the file X for a short distance over the face of the file X which portion A is provided with means for readily attaching thereto (and detaching therefrom) one end of the strip of emery cloth W which it is desired to mount on the file X and for this purpose this portion A of the "grip" is provided with two (or more) parallel slots A¹ extending across the plate A through which slots one end of the emery cloth is passed up and down as shown in Fig. 3 to thereby attach (in this well-known manner) one end of the emery cloth to this portion A of the "grip." At right angles to this portion A of the "grip" same is provided with two downwardly extending lugs or jaws B with a central opening left clear between same (see Fig. 1) this opening being advantageously narrower at the lower end of said jaws which latter toward their

lower end and on the inner edge thereof are provided with a shoulder B^1 about midway the length thereof; the distance apart between the lower ends of said jaws B being just sufficient to enable same to be passed on to the tang Y of the file X (either with or without removing the handle Z) e. g. said jaws B may be passed sidewise over the tang Y of the file X and by then giving the tang Y or the grip (Fig. 1) a quarter turn the wider part of the tang Y can then slide up through the wider part of the opening between said downwardly extending lugs or jaws B and thus enable the "grip" to be brought up against, or close to, the body of the file or shoulder of the inner end of the file X as shown in Figs. 3 and 6 in which position said "grip" is now locked to the file; while the strip of emery cloth W is drawn taut over the face of the file X and the end folded over the top of the file and secured in this taut position by simply fitting or sliding thereover a strong spring clip or slide (of inverted U-shape) C (see Figs. 2 and 3) whereby the strip of emery cloth W is maintained fixedly in position over the face of the file X .

Referring now more particularly to Figs. 4 and 6, to mount the emery cloth over both sides or faces of the file X one end of the strip of emery cloth W (of about double the length of the file X) has one end thereof attached to the portion A of the "grip" shown in Fig. 4 (which is shown provided with three transverse slots A^1 therein for this purpose) and the lugs or jaws B of this "grip" are passed on to the narrow part of the tang Y and locked or secured to the file as in Fig. 3; while the other end of the strip of emery cloth W (which is passed around the top of the file so as to extend over both faces thereof) is attached to the emery cloth attaching plate D (see Figs. 5 and 6) by threading same up and down through the transverse slots D^1 provided for this purpose in said plate D which latter is also provided with two short transverse slots D^2 and two circular holes D^3 ; the said short transverse slots D^2 being of such size, and in alignment or so positioned, as to be adapted to slide or fit on to the outer ends of the jaws or lugs B of the "grip" Fig. 4. The circular holes D^3 which are provided in that end of the plate D which extends toward the handle of the file are arranged and adapted to permit the ends of the double lever E (which for example may consist of a U-shaped stout wire) to be passed through said holes D^3 and then act as a lever, as shown in Fig. 6, to thereby forcibly draw taut the strip of emery cloth, and when sufficiently taut, the slots D^2 in the attaching plate D can then be slipped onto—so as to engage with—the jaws B of the "grip" Fig. 4 that thereby said devices (Figs. 4 and 5)

and the strip of emery cloth attached thereto are all locked and held tightly and very securely on the file X .

It will be obvious that my present invention may be employed in conjunction with any other suitable body or backing in place of the file for example I may employ any suitable wooden or metal blank of suitable width or length or shape with a tang or shaft or handle of any suitable shape as desired, the aforesaid gripping device or the jaws thereof being modified or shaped accordingly to suit the size and shape of said tang, shaft or handle with which same is to fit over and engage.

As a modification of the aforesaid grip; when the handle of the file or other holder can be readily removed and replaced, then that part of the grip which fits on or over the tang or equivalent may consist of a plate having a hole therein adapted to slip on over the end of the said tang or equivalent.

What I claim is:—

1. A device for mounting and holding emery cloth and the like, consisting of a backing or support having a tang at one end, a gripping device having a portion thereof adapted to be readily attached to and detached from the tang of the said support, and another portion at or about right angles to the first-named portion, adapted to have one end of said emery cloth attached thereto and detached therefrom, and means adapted to secure the other end of said cloth with relation to said support to hold the same taut thereon.

2. Means for mounting and holding emery cloth and the like, consisting of a support having a tang at one end, a flat plate adapted to extend from the tang for a short distance over the face of the said support and provided with transverse slots for readily attaching or detaching one end of the strip of emery cloth, and jaws extending at or about right angles from said flat plate adapted to engage and lock on the tang close up to the tang end of the said support, and a spring clip or slide adapted to fit over the outer end of the support and the emery cloth folded over said end to thereby hold the emery cloth securely and tautly on the support, and means adapted to secure the other end of said cloth with relation to said support.

3. Means for mounting and holding emery cloth and the like, consisting of a support having a tang at one end, a flat plate adapted to extend from the tang for a short distance over the face of the said support and provided with transverse slots for readily attaching or detaching one end of the strip of emery cloth, and jaws extending at right angles from said flat plate adapted to engage and lock on the tang close up to the tang end of the support, and a flat plate

- provided with transverse slots for attaching or detaching the other end of the emery cloth and further provided with two short slots corresponding with and adapted to fit 5 over the projecting ends of the jaws on the first-named plate and draw taut the emery cloth over both faces of the support, when said two plates are forced into engagement with one another on the support.
- 10 4. Means for mounting and holding emery cloth and the like, consisting of a support having a tang at one end, a flat plate provided with transverse slots therein and jaws at right angles thereto, shoulders on said 15 jaws and spring means of inverted U-shape, adapted to fit over both the outer end of the support and the emery cloth folded over said end to thereby hold the emery cloth securely and tautly over the support, and 20 means adapted to secure the other end of said cloth with relation to the support.
5. Means for mounting and holding emery cloth and the like, consisting of a support

having a tang at one end, a flat plate provided with transverse slots therein and jaws 25 at right angles thereto, shoulders on said jaws, and a second flat plate having transverse slots therein for attaching and detaching the other end of the emery cloth, shorter transverse slots in alignment with one another and adapted to fit over the projecting ends of the jaws on said first mentioned plate fitted on the tang of the support, the last mentioned plate being provided with means to permit the application thereto of 30 a tauting tool, to thereby draw taut the emery cloth and lock the two said devices to one another and to the support with the emery cloth stretched taut over both sides 35 of the support.

In witness whereof I have hereunto set my hand in presence of two witnesses.

HAROLD EDENBOROUGH.
